UNDER ARM PROTECTOR

George H. Souther, Jr., Columbiaville, N. Y.

Application June 23, 1933, Serial No. 677,215

8 Claims. (Cl. 2—53)

My invention relates to an underarm absorbent protector and deodorant particularly adapted for use by men, who are inclined to perspire very freely in the portions of their bodies directly underneath the arms, and who desire to protect their garments against perspiration and odor.

This invention has for its object to provide a protector of this character, which is made up of highly absorbent material containing a deodorant, and which is detachably hung, as a hammock, in the arm hole of a garment, so as to fit snugly within the arm pit in direct contact with the wearer's body.

Another object of this invention is to construct an underarm protector of the character hereinafter described, which is provided with end portions adapted to be upturned when being worn so as to form stops or corks, front and back, whereby excess moisture is absorbed and prevented from seeping outwardly and into the garment above the region actually covered by the protector.

A still further object of the invention is to incorporate in the device, a check or moisture-proof layer, whereby the protector, having absorbed a maximum quantity of moisture, is capable of holding the same within itself and against possible pick-up by any part of a garment coming into contact therewith.

I accomplish these objects by means of the protector, one embodiment of which is described in the following specification, set forth in the appended claims, and illustratively exemplified in the accompanying drawing, in which Figure 1 is a top plan view of a protector, parts being broken away to disclose otherwise hidden parts; Figure 2 is a substantially longitudinal sectional view, taken on lines 2—2 of Figure 1; Figure 3 is a side elevational view of the protector in its folded position and ready to be placed within the arm hole of a garment; Figure 4 is an end elevational view of the protector in its folded position; and Figure 5 is a sectional view of a garment showing the arm hole thereof and protector attached.

Referring to the drawing, 10 denotes the outer wrapping which consists of a length of cotton gauze disposed two or more times about an absorbent filler 11. The projecting ends of the gauze beyond the filler being folded against the under side of the protector. The filler 11 in the present instance comprises, from the bottom or under side up, a layer of crepe paper sheets 12, a sheet of waterproof material, such as paper 13,

a layer of gauze 13^a, another section of superposed sheets of crepe paper 14 of considerably greater thickness than the first layer 12, a single piece of gauze 15, and still another section of superposed sheets of crepe paper 16 disposed on the gauze 15.

The protector is shaped with a rectangularly shaped mid-portion A, substantially oval-shaped end pieces B and restricted neck portions C between A and B. After the wrapper 10 has been wrapped about the filler 11 and the ends folded against the under side, a pair of narrow strips of gauze 17 are wrapped about the neck portions C and the ends of each strip are tied together on the under side of the protector, as illustrated in Figures 2 and 4. The strips 17 tend to hold the wrapping 10 firmly in position about the filler 11 and to define the end pieces B apart from the intermediate body portion A. A staple 18 is driven through the strip 17, wrapper 10 and filler 11 in the mid portion of each neck section C to insure the filler in fixed position. Loosely attached to each staple 18 on the under side of the protector is a hook 19 or any other fastening means suitable for effecting a detachable connection with the portion of a garment to which the protector is to be attached. It will be understood that a hook is shown merely as one possible means by which the connection may be made. The hook in the present instance engages the arm hole seam 20 of a shirt, as indicated in Figure 5.

Referring now to the application of my under arm protector, reference will be had particularly to Figures 3, 4 and 5. From the flat pad 35 arrangement illustrated in Figures 1 and 2, the completed protector is folded longitudinally upon itself at its intermediate portion A so as to bring the two opposite side edges side by side and directed downwardly. This position of the mid portion A will allow the ends B to be turned upwardly along the neck portions C. As a result, the hooks 19 may be swung upwardly from the outer surfaces of the upturned ends B to be engaged in the arm hole seams 20.

It has been found desirable to cause the waterproof piece 13 to be folded upon itself transversely thereof in two or more places in order to enable the protector when folded longitudinally for use to take a comfortable outward curve and consequently a properly fitted position in the arm pit of the wearer and at the same time offer the necessary protection required to prevent moisture from seeping through to the bottom or under side of the protector.

In practice when the paper 13 is folded and in place, it does not project beyond the dimensions of the mid portion A in any direction, as illustrated particularly in Figure 1.

5 The present invention, when applied, does not rest upon the lower portion of the arm hole seam for support, but being attached at its ends to the seam at the proper height, virtually becomes a hammock closely embraced by the 10 wearer's flesh in the arm pit, while the ends B in their upstanding position hug snugly to folds in the flesh coming out from under the arm in front and back and form what might properly be termed corks to prevent escape of excess perspiration over and above the region actually 15 covered by the absorbent protector.

It will suffice to state that the protectors, according to the present invention, may be easily attached to the wearer's garment, and just as 20 easily detached and discarded when they have served their purpose. The protectors can be manufactured very cheaply because of the materials used in their construction, and as a consequence, may be sold at a very modest amount.

25 Any of the well known deodorants may be used upon the filler to remove the unpleasantness which otherwise follows excessive perspiration allowed to remain upon the body.

Having described my invention, as applied 30 particularly to under arm protectors, it must be understood that the specific construction set forth may be applied with equal results to the so-called sanitary pad or napkin.

What I claim is:

35 1. As an article of manufacture, an under arm protector, comprising a filler of superimposed layers of absorbent material, and an interposed layer of moisture proof material folded upon itself transversely thereof to form pleats, whereby the protector is capable of being folded longitudinally along an outward curve to fit to the arm pit in any position of the arm.

40 2. As an article of manufacture, a protector to be supported in the arm pit of the wearer,

comprising a filler of layers of absorbent material and a moisture-proof layer adjacent its under side, said filler having a mid-portion to be folded upon itself and end portions turned upwardly to form corks front and back at the ends of the arm pit.

5 3. As an article of manufacture, a protector to be supported in the arm pit of the wearer, comprising a wrapper, a filler within the wrapper of absorbent layers of material and a moisture-proof layer interposed in the material adjacent its under side, said filler having a rectangular mid-portion, end portions and intermediate restricted portions between said end and mid-portions, bands tied about the filler and wrapper in the restricted portions, and means for attaching the protector to the wearer's garment.

4. A protector, as claimed in claim 3, including a layer of gauze interposed between the absorbent layers to prevent deterioration thereof when the latter are saturated with moisture.

20 5. A protector, as claimed in claim 3, in which the layer of moisture-proof material is folded upon itself one or more times and confined to 25 the mid portion of the filler.

6. A protector, as claimed in claim 3, in which the means for attaching the protector to the wearer's garment comprises a detachable fastener attached at one end to the under mid-section of the restricted portion and at the other 30 provided with means to engage the garment.

7. A protector, as claimed in claim 3, including staples inserted in the wrapper and filler at the restricted sections to hold them together.

35 8. A protector, as claimed in claim 3, in which the wrapper comprises a length of gauze wrapped longitudinally two or more times about the filler and the projecting ends turned over and against one side, and means driven through 40 the wrapper, filler and bands to hold them together.

GEORGE H. SOUTHER, JR.
